UNITED STATES PATENT OFFICE.

ALBERT T. KELLER, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

OPEN-HEARTH FURNACE.

Application filed December 5, 1921. Serial No. 520,045.

To all whom it may concern:

Be it known that I, ALBERT T. KELLER, a citizen of the United States, and residing at Bethlehem, Northampton County, State 5 of Pennsylvania, have invented certain new and useful Improvements in Open-Hearth Furnaces, of which the following is a specification.

This invention relates to regenerative furnaces and particularly to reversible furnaces 10 of the type used in the production of steel by the open hearth process.

The object of the invention is to provide a furnace of this class embodying a novel 15 and improved end construction by means of which the rate of gas consumption may be increased and hence the productive rate or output of the furnace increased, without shortening its effective life. One form of 20 the invention is illustrated in the accompanying drawings in which:

Figure 1 is a central vertical longitudinal section through one end of the furnace;

Figure 2 is a section on line 2—2 of Figure 1;

Figure 3 is a section on line 3—3 of Figure 1;

Figure 4 is a section on line 4—4 of Figure 1;

Figure 5 is a section on line 5—5 of Figure 1;

Figure 6 is a view of a portion of the end of the furnace showing details; and

Figure 7 is a vertical section through 35 a portion of a modified form of furnace.

The hearth is indicated at 10 and the roof at 11, these members converging at the ends of the furnace to form a throat 12 through which the air and gas are introduced at the 40 inlet end of the furnace and the products of combustion make their escape at the outlet end the two ends of the furnace being preferably alike in construction. Flues leading to air and gas regenerating chambers (not shown) are indicated at 13 and 14 respectively. The gas flue 14 has a flue 15 or uptake leading upwardly therefrom which branches at a point opposite the combustion chamber, one branch 16 extending 45 horizontally inward toward the throat 12 and terminating in a port 17 and the other branch extending upwardly to communicate with the channel 18 which opens into the upper part of the throat. A valve or damper

19 is fixed on a rotatable rod 20 and is adapted to be turned either to its horizontal or full line position (Figure 1) to block communication between flue 15 and channel 18, or to be turned to its dotted line position to block communication between flue 15 60 and branch 16.

The flue 13 leading from the air regenerating chamber has two uptakes 21 extending upwardly therefrom each of which branches at a point substantially horizontally opposite the branch 16 of the gas flue, one branch 22 of each flue leading to the channel 23, which has substantially the form of an inverted U, and which terminates at its forward end in a port 24 of similar shape. The other branches 25 of the air flues 21 extend vertically upward and communicate with the channel 18 at the top of the furnace. Valves or dampers 26 are positioned to control communication between flues 21 and channels 18 and 23. These dampers are fixed upon rods 27 which are rotatably mounted in the walls of the furnace so that they may easily be turned from full to dotted line position (Figure 3) by the operator. Preferably rods 20 and 27 are operatively connected together by suitable gearing and to rotatable shaft 28 on which hand wheel 29 is mounted, so that a furnace attendant can simultaneously move the dampers 26 and 19 from vertical to horizontal position or vice versa, the three dampers moving simultaneously to either horizontal or vertical position.

At the inlet end of the furnace the three 90 dampers occupy the positions illustrated in full lines in Figures 1 and 3 so that air and gas are constrained to flow through channel 23 and branch 16 respectively, to the air and gas outlet ports 24 and 17. However at the 95 opposite end of the furnace the dampers are arranged vertically, or in their dotted line positions, so that the hot products of combustion pass through the large channel 18 and into flues 15 and 21 and thence to the regenerators. No exhaust gases pass out through ports 17 and 24 and these ports are thereby preserved against the well known corrosive action of the hot gases and drops of slag carried thereby. The channel 18 also has 100 an effective cross sectional area at its narrowest part greater than the combined area of ports 17 and 24 so that the port area

for the outgoing products of combustion is greater than the port area for the incoming gas and air.

If desired, the valve 19 may be replaced by a non-movable partition as shown in Figure 7, and in such case a portion of the gases issuing from the furnace at the outlet end will pass through channel 16 and thence down channel 15, as well as escaping downwardly through flues 21.

The invention may be modified in other ways, as will be apparent to one skilled in the art, within the scope of the appended claims.

Having thus described the invention what I claim as new and desire to secure by Letters Patent is:

1. An end construction for regenerative furnaces having uptake flues for air and gas communicating with a combustion chamber, a channel adapted to communicate with each of said flues and with the combustion chamber, and means for controlling communication between the said channel and the said air and gas flues.
2. An end construction for regenerative furnaces having air and gas uptake flues opening into a combustion chamber through suitable outlet ports, a channel opening into the combustion chamber above said outlet ports and connecting with the said air and gas flues in rear of such outlet ports, and means for controlling communication between said channel and the air and gas flues.
3. An end construction for regenerative furnaces having air and gas uptake flues discharging into a combustion chamber, a channel adapted to communicate with each of said air and gas flues and with the combustion chamber, said channel having an effective cross sectional area greater than the combined cross sectional area of the outlet ports of the air and gas flues, and means for controlling communication between said channel and the air and gas flues.
4. An end construction for regenerative open hearth furnaces having two uptake flues, each of said flues being adapted to communicate with the combustion chamber through either of two different ports, and means for controlling communication between each flue and its associated ports.
5. An end construction for regenerative

open hearth furnaces, having two uptake flues and three ports opening into a combustion chamber, each flue being connected to two of said ports, and means for controlling communication between each flue and its associated ports.

6. An end construction for regenerative open hearth furnaces, having two uptake flues and three ports opening into a combustion chamber, one of said ports having an effective area greater than the combined areas of the other two and being connected to each of said uptake flues, each flue being connected to one only of the two smaller ports and to the large port, and means controlling communication between each flue and its associated ports.

7. An end construction for regenerative open hearth furnaces, having two uptake flues and three ports opening into a combustion chamber, each flue being connected to two of said ports, and means for opening or blocking communication between each flue and one of its associated ports, said means being simultaneously operable.

8. An end construction for regenerative open hearth furnaces, having two uptake flues and three ports opening into a combustion chamber, each flue being connected to two of said ports, and means including operatively interconnected dampers for opening or blocking communication between each flue and one of its associated ports.

9. An end construction for regenerative open hearth furnaces having two uptake flues and three ports opening into a combustion chamber, each flue being connected to two of said ports, and means including pivotally supported dampers operatively connected together for simultaneous movement, for simultaneously opening or blocking communication between each flue and one of its associated ports.

10. An end construction for regenerative open hearth furnaces, having a plurality of uptake flues and a plurality of ports opening into a combustion chamber, each flue being connected to two of said ports, and means for controlling communication between each flue and its associated ports.

In testimony whereof I hereunto affix my signature.

ALBERT T. KELLER.
